JAMES E. BEARDSLEY, AUGUSTUS F. BOYLE, ENOCH M. LEWIS, AND MICHAEL A. CLANCY, OF WASHINGTON, DISTRICT OF COLUMBIA.

Letters Patent No. 69,389, dated October 1, 1867

IMPROVEMENT IN APPARATUS FOR RECORDING VOTES.

The Schedule referred to in these Letters Patent and making part of the same.

TO ALL WHOM IT MAY CONCERN:

Be it known that we, JAMES E. BEARDSLEY, AUGUSTUS F. BOYLE, ENOCH M. LEWIS, and MICHAEL A. CLANCY, of the city of Washington, in the county of Washington, and in the District of Columbia, have invented an Apparatus for Calling the Roll and Recording the Votes in Deliberative Assemblies; and we do hereby declare that the following is a full, clear, and exact description thereof, reference being had to the accompanying drawings, and to the letters of reference marked thereon, making a part of this specification.

Our invention consists in the construction and arrangement of mechanism for "taking the votes of legislative or other assemblies" in a short space of time, and without the confusion now oftentimes experienced in collecting properly the votes of members *viva voce*.

This invention is intended to be placed at the principal table or desk in the hall, or in any conspicuous or suitable place. A device, the counterpart of the one herein described, will be used for recording the negative votes, while this one is used for the affirmative, or *vice versa*. A wire, or other suitable material is passed from the apparatus to the table of the voter, so that upon drawing the affirmative or the negative wire his vote is recorded, and indicating to himself or his fellow-members how or when he has voted. In addition to the voting this invention prints the name of each voter, so that the teller in summing up has the names and the record of the vote all at one operation. This machine may also be used to call the roll of the members.

Figure 1 of the annexed drawings represents the front of the machine with a broken section, showing the rollers around which is passed the paper to be printed.

Figure 2 represents a front view of the second interior plate or disk of the machine.

Figure 3, a small section of the rear of the drum, showing the spring-catch.

Figure 4, a rear view of the circular disk in the rear of the plate B, showing the cams and springs which operate the voting-plates.

Figure 5, a section of the apparatus for voting and printing.

Figure 6, a front view of the main-spring, which is attached to the front of the rear plate D, showing the construction of the pawls and ratchets connected thereto.

Figure 7, a view of the metal plate, within which the end of the pawl *n* on the front of the spring *H* is passed.

Figure 8, an interior view of the machine taken between the two rear plates.

Figure 9, a view of the printing-drum and rollers.

Figure 10, a front view of the disk C.

Figure 11, a side elevation of the machine.

In the annexed drawings, making a part of this specification, A represents a circular metallic disk, which is correctly divided into sections on its face, and provided with a number on each section. This dial may have any required amount of numbers, and can be made of a size to suit the size of the machine, or the sized body for which the machine is intended to be used. A circle is made inside of the numbers, and a flange, A', formed on the disk, which projects inwards, and is provided with a series of slots, a' a', at regular intervals, the object of which will be hereinafter set forth. The formation of the flange A', as described, leaves a suitable receptacle for the insertion of the drum E, to which are attached the rollers for printing, so that when thus placed the outer face of the drum is flush with the face of the dial, which dial may be ornamented in any suitable manner. Ordinarily the entire machine will be enclosed in a neat box with the dial-plate outside. Directly in the rear of the flange A' is the disk B, fig. 2, which is also circular, and is connected to the disk A by suitable bolts *a a*. The circumference of this disk has a series of narrow slots, placed in pairs, as shown, to allow the elevation or depression of the U-shaped bar, to which is connected the voting-indicator. This disk has also a narrow slot below and between the slots *y* for the passage of the ends of the metal plates P, to which the type-jacket and type are fastened. The central portion of the plate is taken out, so that a four-armed bar, F, is formed, which bar has two of its points, f' f', slightly bevelled for the operation of the double-catch spring d' on the back of the drum, to be set forth hereafter. In the rear of this disk B is a smaller circular plate, G, fig. 4, which is placed between disks B and C. Said plate is used for throwing the plates P in position for voting, and is pro-

vided with a small metal plate with a curved point, h , on one of its sides, which extends beyond the circumference thereof, and which is placed above a spring, h' , lying on the side of the plate. On the other side of the plate, nearly opposite the plate h , is formed a small metal jacket, into which is set a small bar, i , having a rounded upper end, and a pin on its lower end, which passes through the jacket and is attached to the rear spring j connected to the central shaft, by which it is operated. In the rear of this plate G is the disk C , fig. 10, provided with two narrow grooves $v v'$ near its centre, having springs transversely placed at the top of each, and into which grooves works a pin, m , on the face of the bar i . It will be understood that the plate G is used for the twofold purpose of readjusting the voting-bars P and for operating the large hand l on the dial-plate, as well as for the purpose of operating printing-drum E . On the shaft c , in front of the plate G , there is a hollow shaft, d^a , having a ratchet-wheel, k , which lies in an opening in the centre of this plate, which ratchet has a pin on its face, against which is the point of the metal jacket r^2 . The forward end of bar h has a stem, which is passed through this jacket, and which will catch into the ratchet when the said bar is thrown down by its passage under the voting-bars. (See fig. 2, dotted lines.) l represents a lug on the face of plate G , which catches into the double catch d^2 on the back of the drum E , for revolving the same. $P P P$ represent the voting-bars, the ends of which are passed into openings in the plate C , and lie on the face of said plate, so that their inner ends rest just outside of the periphery of the plate G , and to be thrown in position by the bar i on said plate. Between the outer ends of these bars there is a stud on the face of this disk, which has a steel spring, $W W$, fig. 10, connected to it, so that the ends thereof shall press upon the outer ends of the plates P , and throw them into position for the plate h to operate them. It will thus be seen that one spring is made to answer for every two of the voting-bars P on the disk.

To illustrate the mode of voting, we will describe one apparatus, the parts of which are shown in fig. 5 of the annexed drawings. Similar devices to the ones therein shown are to be used for and in the rear of each number on the dial-plate.

Between the disks B and C are the plates P , as heretofore described. These plates are narrow strips of metal, having an ear at the upper end which extends through and slightly to the rear of the disk C , and a portion opposite this ear, which extends through the plate B , as seen in fig. 2. The edges of these plates, which lie against the face of disk C , have two small notches cut into them, $x^1 x^2$, while the lower ends have projecting points, which lie in the slots in plate C . z represents the metal casing, which is connected to the forward part of the plate P , and into which are placed the type-jacket and type, which are securely held therein by the set-screw, as shown. The red lines in fig. 5 show the position of the disk B , with the type in front of said disk. Upon the rear face of disk C there is a series of flat metal springs, R , (see red lines, fig. 10,) which radiate from the centre of the disk, and are pivoted near the horizontal shaft c , which passes through the centre of the entire machine. One of these springs R lies in the rear of each bar P , and is provided with a pin, t' , (see figs. 2, 10, and 5,) which passes through the disk C near the inner end of the plate P . b' represents a pin, having a coil spring around it, which extends from the rear of the rear plate D to and through the plate C , where the end is rested in one of the notches x^1 or x^2 in the edge of plate P . This pin has two small pins near its forward end, and passes through the top portion of the spring R . Between the two small pins on the end of this pin is placed a slotted lever, N , which lever is pivoted to the ear of the bar P , and extends up above the machine. The object of this lever is to change the vote of the member who desires to do so after having voted, and without necessitating a change of all the voting-bars, by the method to be fully set forth. O represents a U-shaped metal bar, having a square or other shaped metal plate, X , at its forward end, with any number on its face, which we prefer to call the "voting-indicator." The forward parts of this bar pass into the slots y in the disk B , while at the rear end is a bar, having a narrow slot where it is pivoted to the rear of disk C . The end of this bar is pivoted to a small upright bar, s^3 , which said bar is also pivoted to the extremity of the ear on bar P . The end of rod b' is slotted, as shown, and into which is secured the upper end of an angular bar, b , which bar is pivoted at the bend thereof to studs in the rear of plate D . The wire which runs from the desk of the member is attached to the other end of this bar b , so that by drawing the wire the end of the bar is carried down, drawing the pin b' to the rear, and releasing its end from the notch x^2 in plate P , causing said plate, by means of the spring W , to be forced to the centre, carrying with it bar s^3 and the rear end of bar O , this causing the voting-indicator X to be thrown up, as shown in fig. 2. When the end of pin b' is taken from notch x^2 , the spring around it is compressed, so that immediately after the bar P is drawn far enough towards the centre of the plate the pin will be again carried, by the recoil of the spring, to the next notch, x^1 , and hold the indicator in position. H represents a coil spring, within a suitable box around a short shaft passing from disk D to disk C , having its bearing on the front of disk D . Upon this shaft, between the disks, are two ratchet-wheels, $p p'$. The ratchet p is held by the pawl n and spring o' , and is placed upon the front of the spring-box H . Pivoted on the face of this ratchet are two eccentric-shaped pawls $o o$, (see fig. 6,) which are nearly semicircular in form, and provided with heads that project forward, so as to catch into the teeth of the forward ratchet p' . This latter ratchet is secured upon the rear face of the cog-wheel s , which encircles the shaft. K represents a clutch-fork, which extends above the top of the machine, and clutches around a collar, r , around the shaft in front of the wheel s . On the opposite side of wheel s , on said shaft, between the pawls $o o$, is a conical-shaped metal block, q , which is connected to the collar r at the end of the clutch K by means of small pins $x x$, which pass through the wheel s and ratchet p' . The clutch K has its fulcrum just above the collar r , and has a metal plate, m^2 , connected to it near its top. This plate m^2 , fig. 7, has a tenon formed on each end, and works back and forth with the lever or clutch in an opening in the disk D . The top of the vertical pawl n passes through an L-shaped opening in this plate, and by this means is released from the ratchet p , as desired. m^1 is a slotted plate, through which the top end of pawl m is passed, which acts as a guide to keep said pawl in

proper position. *c* represents the main shaft, which passes through the entire machine. At the rear of this shaft is wound a small coil spring, *I*, and is also provided with a cog-wheel, *t*, between the disks *D C*, and which said wheel meshes into the cog-wheel *s'* upon a short shaft opposite to spring-shaft. There are two cog-wheels upon this shaft, one of which meshes into the wheel *t*, while the other is meshed into wheel *s* on the main-spring-shaft. *d'* represents a hollow shaft encircling the shaft *c*, and extending to the front of the dial-face. This shaft has a small spring on its outside, *x'*, so that it may be held tightly within the socket *f'*, fig. 2, in the centre of the plate *F* of disk *B*. *E* represents the printing-drum, which is placed in the receptacle formed in the dial-plate *A*, and which said drum is composed of two circular disks, with an inner circle, *g*, fig. 9, for the passage of the ends of the roller-bars. Between the disks of this drum is placed a series of rollers, which have tenons on each side, *e e*, figs. 1 and 9, that work into small grooves on the disks. These rollers *f* are set into metal cups having pins, which radiate to the common centre, said pins being provided with spiral springs, so as to keep the outer surface of the rollers to the circumference of the disks. *W'*, figs. 1 and 11, represents the reel on which the paper is wound, and which is passed from said reel down under a roller, *g*, into an opening in flange *A'*, and passed around the entire series of rollers *ff* in the drum *E*. On the outside of the flange *A'* is passed an inked ribbon, (not shown,) which is wound around the reel *w*, and, after passing around the flange, connected to the opposite reel *w'*. Between and beneath these reels are small rollers 4 5 6 7, under which are passed the band and paper, so as to keep them stretched and guided.

Having described the mechanism of this invention we will now proceed to set forth in detail the practical operation thereof.

It will be understood that the principal parts of the machine are constructed of metal, and that nearly all the portions radiate from the common centre, (shaft *c*.) In putting the machine together the small spring *I* on the rear end of shaft *c* is wound as tightly as it will admit of being, and the large spring *H* is wound from the rear of disk *D* by a key on the end of its shaft. Usually the plates *P* are thrown to allow the bars *b'* to rest in the notches *x'*, so that, as soon as a member has voted, the plate *X* will at once be thrown up, and indicate the fact. After the voting is finished it becomes necessary to count the votes, print the names, and to readjust the machine for the next operation. These functions are performed by means of the springs and gearing in the rear part of the machine. It will be seen that the dial-plate is provided with a large and small hand, 1 2, and that the large hand is encircled around the hollow shaft *d'*, while the small hand is around the main shaft *c*. After the members have voted the operator throws the clutch *K* towards the disk *D*, thereby forcing the cone *q* between the points of the pawls *n o*, releasing the ratchet *p'*, and causing the forward movement of the disk *G* stationed on the shaft *c* by means of spring *I* on said shaft. As the disk *G* is carried around, its plate *h* strikes under the inner edge of each of the plates *P* that have been operated by the voter. As it is thus passed the pin *r'* is forced into the ratchet *k*, and causes the large hand 1 to be carried to one of the numbers on the dial. As the disk *G* is carried around, the end of the bar *h*, being thrown out by its spring, will strike under the bar *P* that has been operated upon. This will cause the pin *r'* to catch into the ratchet and carry hand 1 to the first number on the dial. Should one member not vote, the spring will keep plate *h* out, and the pin out of the ratchet, causing the hand to remain stationary until the plate shall again strike a bar that has been operated upon. Both the large and small hands start at one time if the number one member votes, and the small hand will revolve entirely around the dial without stopping. The small hand 2 will revolve around the entire plate, as aforesaid, while the large hand will indicate the exact number of the votes taken. When passing around, the plate *G*, by means of its lug *l*, is caught into the rear of the printing-drum *E*, between the shoulders on the double catch *d'*, and revolves the drum, so that the rollers *f* will pass under the slot in the flange *A'*, above which are the type and box, already thrown down by the bars *P*, so that the impression with the member's name is taken on the paper as it passes. It is only necessary for the drum to partially revolve to impress, consequently the lug *l* is released from the catch *d'* between the bevelled points *f' f'* in the plate *F*. After the printing is done and the votes counted the clutch *K* is again brought forward, so that the shaft is allowed to be turned by means of the large spring *H*, which again winds up the small spring *I*, and the disk *G* made to turn backwards, so that the curved point *i* will strike the pins *t'* on the springs *R*, so as to cause the throwing outwards of the bars *P*, whereby they are readjusted for the next voting. It will be seen that the point *i* forces the bars *P* outward, and the springs *R* force back the rods *b'*, so that said rods on the recoil of their springs will catch into the second notch *x'* as the bars are forced up. Upon the face of the drum *E* there is a card, *d*, for the name of each member, which is directly inside of the number on the dial. In the backward movement of disk *G* the pin 9 on the outside of the pin *r'* catches against a small pin, 8, on the face of the ratchet, and thereby returns the ratchet, and brings the hands 1 2 back to their normal positions.

Having thus fully described our invention, what we claim as new, and desire to secure by Letters Patent, is—

1. The arrangement of the bars *P* with jacket and type *z*, bars *O* with indicators *X* connected to bars *P* by the short bar *s'*, rods *b'*, and springs with angular bars *b*, when used with the disks *C* and *D* and lever *N*, in the manner and for the purposes herein specified.
2. The dial-plate *A*, with its flange *A'* and hands 1 2, when arranged in combination with the drum *E*, as constructed in the manner and for the purposes herein set forth.
3. The metallic disk *C*, with its springs *W W* and slots, and provided with the radiating flat springs *R* on its back, in the manner and for the purposes specified.
4. The disk *B*, provided with narrow-paired slots *y y* for guiding the U-shaped bars *O* and plate *F*, as constructed and arranged as set forth.
5. The circular disk *G*, with point *i*, pin *m*, and spring *j* on its rear face, and with bar *h*, spring *h'*, pin *r'*, and pin 9 on the front face, in combination with the hollow shaft *d'* and ratchet *k*, as and for the purposes herein fully described.

6. The arrangement of the clutch K with cone q and pawls o , in combination with the ratchets $p p'$, spring-shaft and spring H, plates $m^1 m^2$, and cogs $s s^1$, in the manner substantially as and for the purposes herein specified.

7. The drum E, with its rollers ff , band g , and double catch d^2 , when arranged and used in the manner and for the purposes herein specified.

8. The disks A, B, C, D, and G, with the drum E, when constructed as specified, with the voting devices and gearing for taking, counting, and printing the voters' names in the manner and by the operation substantially as herein fully set forth.

In testimony that we claim the foregoing we have hereunto set our hands this 19th day of June, 1867.

JAMES E. BEARDSLEY.
